SUPPORT STRUCTURE

Louis D. Elliott, New London, Iowa

Application August 11, 1937, Serial No. 158,580

2 Claims. (Cl. 189—34)

My invention relates to improvements in support structures and more particularly to structures designed for supporting mail boxes and the like.

5 One of the principal objects of my invention is to provide a support structure for mail boxes or the like which is simple in construction, durable in use and economical in manufacture.

Another object of my invention is to provide 10 a support structure of the above described character equipped with means whereby the same may be readily positioned in the ground and adjusted to various heights in relation thereto.

A further object of my invention is to provide 15 a structure of the above described character which may be readily moved from one location to another without disassembling the same.

Other objects and advantages will be apparent 20 from the following description, appended claims and annexed drawing.

Referring to the drawing wherein like reference characters designate like parts throughout the several views:

Fig. 1 is a perspective view of my invention.

25 Fig. 2 is a detail perspective view of an upper end of one of the uprights.

Fig. 3 is a detail sectional view taken on a line 3—3 of Fig. 1.

30 Fig. 4 is a side elevation of the detail structure shown in Fig. 3.

In practicing my invention, I provide an elongated quadrifrontal frame, each of the corners comprising an upwardly and inwardly inclined upright member 5 of angular formation in cross section and terminating at the upper end thereof in a laterally extending flange 6 having an extended portion 7. Each of the uprights are formed of a pair of longitudinally extending right angularly disposed integrally connected sections. 35 The end of one section is transversely cut to form a portion integral with a like size portion integrally fashioned on the other section and said portions are arranged to form an elongated right angularly disposed horizontally extending flange constituting a seat.

40 Each of said flanges or seats are formed with an aperture 8 for registry with similar apertures formed in a pair of bed plates 9 secured thereon by means of suitable rivets or the like. A mail

box M of ordinary construction is secured on the bed plates 9 and embraced by the offset ends 10.

The upright members 5 are secured together in spaced relation by groups of transversely extending cross braces 11 connected thereto intermediate of the upper and lower ends thereof. Pairs of crossed diagonal braces are connected to the ends of the upper and lower transversely extending cross braces on each face of the frame 10 by means of suitable bolts 13, or the like.

The lower ends of the upright members are pointed for easy insertion in the ground. Obviously, the structure may be inserted in the ground at any desired height to give ready access to the 15 mail box.

Due to the compactness and simplicity of the structure, the same may be readily removed from the ground and positioned in another location without disassembling any of the parts.

It is to be distinctly understood that various changes and modifications in construction and arrangement of parts may be resorted to without departing from the spirit of the invention or scope of the appended claims.

Having described my invention, what I claim is:

1. A structural unit comprising, a member formed of a pair of angularly related sections with the end of one section terminating in a flange lying in a plane angularly related to and extending away from both of said sections, said flange formed with a lateral portion extending laterally relative to said end of said other section and said flange and portion cooperating with the end face of said end of said other section to provide a seat.

2. A structural unit comprising, a member formed of a pair of angularly related sections of which the ends of the two are adjacent, one of said ends terminating in a flange lying in a plane substantially right angularly related to and extending away from both of said sections and formed with a lateral portion extending laterally relative of said other end, said flange and portion arranged with faces flush with each other and the end face of said other end to cooperate with the latter to provide a seat.

LOUIS D. ELLIOTT.
